(57) **CLAIM**

The ornamental design for a handgrip for food utensil, as shown described.

DESCRIPTION

FIG. 1 is a front elevational view of a handgrip for food utensil showing my new design, the rear elevational view being a mirror image thereof;

FIG. 2 is a side elevational view thereof, the opposite side elevational view being a mirror image thereof;

FIG. 3 is a top plan view thereof;

FIG. 4 is a bottom view thereof;

FIG. 5 is a front elevational view of an alternate embodiment;

FIG. 6 is a side elevational view of the alternate embodiment the opposite side elevational view being a mirror image thereof;

FIG. 7 is a top plan view of the alternate embodiment; and,

FIG. 8 is a bottom view of the alternate embodiment.

The rear of alternate embodiment shown in FIGS. 5-7 is plain and unornamented. The broken lines are for illustrative purposes only and form no part of the claimed design.
